FAUCET

August L. Voight, Cleveland, Ohio

Application July 29, 1938, Serial No. 221,987

3 Claims. (Cl. 225—5)

This invention relates to a faucet which is particularly adaptable for drawing beer or carbonated beverages.

An object of the invention is to provide a faucet of the character specified and wherein the valve of the faucet is moved positively to its seat.

Another object of the invention is to provide in a faucet of this character means for readily and conveniently adjusting the valve without disassembly of the faucet, wherefore any wear on the valve may be compensated for and dripping or leaking of the beverage from the faucet avoided.

Another object is to provide in a faucet of the character specified positive means for seating and unseating the valve and which operates from beneath the valve and forms in the faucet on the outlet side of the valve seat an obstruction or restriction that acts to agitate the beer or other beverage so that it will rise in the glass or container into which it is being drawn with a swirling motion, and in the case of beer will create the desired creamy foam or head on top of the glass.

Another object is to provide a faucet for drawing beer which is so constructed that when the valve of the faucet is first opened the beer may pass the valve freely and without "spitting".

A still further object of the invention is to provide in a faucet of the character specified means for lessening the shock on the stop pin on the outside of the faucet when the valve of the faucet is opened.

Another object is to provide a faucet of the character described which can be readily assembled and disassembled and which is efficient in operation.

A still further object is to provide a beer faucet which is so constructed that a correct glass of beer can be drawn therefrom with a single opening of the faucet as distinguished from the present faucets which often require two or more openings to obtain the desired head or collar of foam on a glass of beer.

A further object is to provide a faucet which is so constructed that the valve is positively moved to seated or unseated position without the use of springs and wherein the valve can be opened easily with very light pressure upon the handle 50 of the faucet, thus resulting in little wear on the valve and other parts of the faucet and increasing the length of service thereof.

Further and additional objects and advantages not hereinbefore referred to will become apparent hereinafter during the following detailed de-

scription of embodiments of the invention which are illustrated in the accompanying drawing wherein

Fig. 1 is a top plan view of the faucet, a portion of the handle being shown in section;

Fig. 2 is a sectional view through the faucet and is taken substantially on line 2—2 of Fig. 3 looking in the direction of the arrows, the valve being shown in closed or seated position in this view;

Fig. 3 is an end elevational view of the faucet with certain portions thereof broken away and in section;

Fig. 4 is a fragmentary sectional view similar to Fig. 2 but showing the valve and associated parts in open position; and

Fig. 5 is a fragmentary sectional view through a faucet illustrating a modified form of valve operating means from that previously shown herein.

The faucet is preferably in the form of a metal casting and has an inlet portion 10 provided with a bore 11 therethrough which communicates at one end of the portion 10 with a threaded counterbore 12 which forms the means for connecting the faucet to the supply line of the beer or other beverage, as will be well understood. The faucet at the outer end of the portion 10 has an integral portion 13 which extends downwardly from the portion 10 as illustrated in the drawing. The upper end of the portion 13 is of greater diameter than the lower end 13a thereof. The portion 13 of the faucet is provided with a valve chamber 14 that is in communication with the bore 11 in the portion 10. At the lower end of the valve chamber 14 there is provided an annular flange forming a valve seat 15. When the valve is open the chamber 14 is in communication with a bore 16 in the lower part 13a of the portion 13 and said bore 16 forms the outlet passage of the faucet. The portion 13 of the faucet just below the valve seat 15 is provided with an integral outwardly extending rounded boss 17 in which is mounted that part of the valve actuating mechanism to which the handle is operatively connected, as will be later explained.

The valve of the faucet is in the form of the usual seat ball 18 which preferably is formed of rubber and has its lower end of conical configuration, as will be well understood. A rod 19 extends through the ball 18 and is threaded at its upper end to receive a nut 20 which can be adjustably screwed down against the ball to press the latter into engagement with a collar 21 carried by the rod 19 below the ball. The rod 19 also ex-

tends through an opening 22a having curved surfaces, as indicated in Fig. 2, and formed in the end of the arm 22 of a valve actuating member 23. It will be noted that the arm 22 is located intermediate the collar 21 and the head 19a of the rod 19.

In assembling the ball 18 and the rod 19 in the faucet, the rod is passed into the faucet from the outlet end thereof and through the opening 22a in the arm 22 of the valve actuating member 23. Then the collar 21 is positioned on the rod 19 from the upper end of the portion 13, after which the ball 18 is forced upon the rod from the upper end of the portion 13 of the faucet and the nut 20 is screwed down upon the rod to properly position the ball 18. After this has taken place, the upper end of the portion 13 of the faucet is closed and sealed by the cap 24 which is threadedly connected to the faucet, as clearly shown in the drawing.

The cap 24 is provided on its inner side with a cylindrical flange 25 forming a recess, the bottom of which carries a rubber or other bumper 26, it being noted that, when the valve is in closed position as shown in Fig. 2, the upper end of the rod 19 extends partially into the recess formed by the flange 25 while, when the valve is opened as shown in Fig. 4, the upper end of the rod extends into the recess until it contacts with the bumper 26.

The boss 17 on the portion 13 of the faucet is solid except for a centrally disposed slot 27 in which is located the valve actuating member 23 that carries the arm 22. This member 23 is provided with an opening therethrough having a flat wall 23a, and a stub shaft or pin 28 carried by or fixed to the handle 29 is adapted to extend into the opening in the member 23 and is provided with a flat cooperating with the flat 23a. The stub shaft or pin 28, as clearly indicated in Fig. 3, extends through a bore formed in the boss 17 and has its inner end located in the opening in the member 23. There is provided in the boss 17 a threaded counterbore which receives a packing gasket 30 and a gland nut 31 arranged on the stub shaft or pin 28 and screwed into the said counterbore. The boss 17 on the side opposite that in which the pin 28 is arranged receives the headed handle screw 32 which screws into a threaded recess in the inner end of the shaft or pin 28 and holds the handle 29 and the valve actuating member 23 in operative assembled relationship. A suitable packing gasket 33 and a gland nut 34 are arranged in a counterbore in the boss 17 and surround the screw 32, it being understood that said gasket 33 and the gasket 30 provide a fluid-tight arrangement whereby beer or other beverages which may work into the slot 27 will not leak to the outside of the faucet.

The handle 29 adjacent its lower and wider portion is provided with the usual curved slot 35 into which extends a stop pin 36 that projects outwardly from the side of the faucet and limits the movement of the handle in opposite directions. It will be noted that the handle 29 intermediate these ends is curved so that the actuating knob 29a secured to the upper end of the handle is located centrally above the faucet, wherefore the faucet can be operated with equal facility by either a right-handed or a left-handed person.

The parts of the faucet as illustrated in the drawings are so arranged that when the valve or ball 18 is in the seated or closed position, as

shown in Fig. 2, the handle 29 is in substantially a vertical position while the upper end of the rod 19 extends slightly into the recess formed on the flange 25 on the inner side of the cap 24. At this time the pressure of the beer in the valve chamber 14 is acting on the valve or ball 18 and holds the same firmly against its seat. When it is desired to draw a glass of beer or other beverage, the operator merely pulls the handle 29 toward himself or downwardly, and this movement of the handle causes the valve actuating member 23 and the arm 22 to rock in a clockwise direction as viewed in the drawing from the position shown in Fig. 2 to the position shown in Fig. 4. This movement of the arm 22 effects an upward movement of the rod 19 and causes the valve ball 18 to be unseated from the seat 15. The upward movement of the rod 19 is limited by the engagement of the upper end of the rod with the bumper 26 in the recess of the cap 24, and this engagement absorbs a large portion of the shock incident to stopping the opening movement of the handle 29, thus relieving the stop pin 36 and preventing the same from being bent or broken off as so often occurs in faucets now in use. When the valve is unseated, the beer or other beverage will flow from the valve chamber 14 into the outlet bore 16 of the faucet. It will be noted, however, that the collar 21, the end of the arm 22, and the head 23 of the rod 19 form an obstruction in the outlet passage such that the beer or other beverage must flow over or around these elements. This fact causes the beer to be agitated to an extent such that it will rise in the container into which it is drawn with a swirling motion and thereby create a creamy foam on the top of the beer giving the latter the desired head or collar.

When the container has been filled, the operator merely pushes the handle 29 away from him or upwardly, and this movement effects a positive rocking movement of the arm 22 of the actuating member 23 in a clockwise or downward direction to positively draw the rod 19 downwardly and to positively seat the ball or valve 18 on the seat 15, the seating of the valve being assisted by the pressure of the beer in the valve chamber 14. It will be seen that the movement of the valve in either direction, i. e., to open or to close the same, is positively effected and no reliance is placed upon springs or other similar means to effect a tight closing of the faucet.

After the faucet has been in use for a considerable period of time, it might be that the conical lower end of the ball 18 has become worn so that the faucet will drip. When this occurs it is only necessary to remove the cap 24 and tighten the nut 20 against the ball 18 to move the latter more firmly into engagement with the seat 15 to compensate for such wear.

In Fig. 5 there is illustrated a somewhat modified form of the invention and particularly with respect to the manner in which the arm 22 of the valve actuating member is connected to the ball valve 18. In this form a short rod 37 is passed through a straight opening 22b in the end of the arm 22 and said rod is provided with a slotted head 37a and a threaded upper portion 37b. The threaded upper portion is screwed into an elongated internally threaded collar 38. In assembling these parts, the short rod 37 is passed into the faucet through the outlet end thereof and through the opening 22b in the arm 22, while the collar 38 is positioned upon the threaded end of the rod 37 from the upper side of the faucet.

through the valve chamber 14. It will be understood that a suitable tool, such as a screwdriver, cooperating with the slotted head 31a can be used to turn the rod 37 to effect a threaded engagement between the same and the collar 38. The ball valve 18 is then positioned in the chamber 14 from the upper side of the faucet after which a long rod 39 provided with an elongated threaded portion 39a and carrying a nut 40 is passed through the ball valve 18 and by means of the slotted head 41 at its upper end is rotated to screw the same into the collar 38. A faucet employing the construction just described will operate in the same manner as the faucet previously referred to, it being noted, however, that when it is desired to replace the ball valve 18 it is not necessary to remove the rod 37 from the arm 22 or from the collar 38 but merely to unscrew the rod 39 from the collar 38 and then lift the ball valve 18 from the faucet through the upper end thereof. It will also be noted that the nut 40 from time to time can be turned down against the ball valve 18 to force the latter more tightly to its seat to compensate for wear.

25 Although two preferred embodiments of the invention have been illustrated and described herein, it will be understood that the invention is susceptible of various modifications and adaptations within the scope of the appended claims.

30 Having thus described my invention, I claim:

1. In a faucet of the character described, an attaching portion provided with a bore therethrough, a portion at the outer end of said attaching portion provided at its upper end with a 35 valve chamber communicating with said bore and at its lower end with an outlet passage communicating with said chamber, said valve chamber being of greater cross-sectional area than said bore and said passage, a valve seat at the junction of said chamber and said outlet passage, a rockable valve actuating member having an arm located in said outlet passage and provided with an opening, a rod extending through said open-

ing in said arm and through said valve, means on said rod operatively interconnecting the same with said arm and said valve, and buffer means located in said chamber in the path of movement of said rod for limiting the movement thereof in one direction. 5

2. In a faucet of the character described, a portion having an inlet bore therein, a second portion angularly disposed with respect to the first named portion located at the outer end of the latter, said second portion adjacent its junction with the first portion being provided with a valve chamber and a valve seat, said second portion also being provided with an outlet passage communicating with said chamber, the end of said chamber opposite to the valve seat being closed by a removable closure member whereby access may be had to said chamber, a valve in said chamber and normally seating on said seat, a rockable actuating arm extending into said outlet passage, a rod extending through said arm and through said valve and into said chamber, and adjustable means on said rod on opposite sides of said valve which can be adjusted when said closure member is removed without disassembling the valve. 20

3. In a faucet of the character described, two angularly disposed portions one of which is provided with an inlet bore and the other of which is provided with an outlet passage and a valve 30 chamber adjacent said inlet bore and communicating therewith, a valve seat at one end of said chamber, a removable closure member for closing the other end of said chamber, a valve in said chamber, an actuating arm in said outlet passage, 35 a rod extending through said arm and valve and into said chamber and operatively interconnecting said arm and valve, said closure member being provided on its inner side with buffer means limiting movement of the rod in the valve opening direction. 40
